UNITED STATES PATENT OFFICE.

WELLINGTON PARKER KIDDER, OF ROCHESTER, NEW YORK, ASSIGNOR TO ROCHESTER INDUSTRIES, INC., OF ROCHESTER, NEW YORK, A CORPORATION OF NEW YORK.

SILENT-TYPEWRITER TYPE-HEAD-ACTUATING MECHANISM.

Application filed June 15, 1921, Serial No. 477,648. Renewed July 7, 1924.

To all whom it may concern:

Be it known that I, WELLINGTON PARKER KIDDER, citizen of the United States, and a resident of Rochester, in the county of Monroe and State of New York, have invented certain new and useful Silent-Type-Writer Type-Head-Actuating Mechanism, of which the following is a specification.

This invention relates to typewriting ma-

- 10 chines, its objects being to produce compactness and lightness of weight in silently operating typewriting machines; to reduce the expense of construction and assemblage thereof; to effect such a mechanical 15 construction of a low cost sheet metal base that the type heads will be guided positively to the impression point without lateral wobbling; that is, in trade parlance, without throwing the type off their feet; to apply 20 the pressure of the type head actuating mechanism on the type head closely adjacent to the printing characters on the type head for more effective impression, especially in manifolding; to provide for easy adjustment 25 of the type heads relatively to the platen; and to incorporate in the platen shift mechanism means for so supporting it that its weight will be greatly diminished 30 relatively to the pressure required to be exerted by the operator in shifting the platen to bring the impression point to different heights for impression of any one 35 of a series of printing characters on a type head one above another. The sheet metal base, considered from the view point of lightness of weight, cheapness of construction, economy of labor in assemblage and 40 mechanical efficiency, is a most important feature of this invention. The base de- 45 scribed is made from a stamped, sheet metal blank and, compared with a similar base made of separate parts greatly reduces the number of parts to be made and assembled, the reduction in number being from seven- 50 teen parts as heretofore proposed by me to one part; and at the same time such a rigidity is given to its integral, vertically slotted guiding webs described below that all transverse canting or wobbling of mem- 55 bers of each type head actuating mechanism guided by such slotted webs is practically eliminated.

In the accompanying drawings forming a

part hereof and illustrating my invention:

Fig. 1 is a partial top plan view of a type-writing machine embodying the features of my invention; parts being broken away for greater clearness, and the view being partially diagrammatic for better illustration of the locations of the various constituent mechanism shown in detail in other figures.

Fig. 2 is a sectional elevation from front to rear of the machine corresponding to line 2—2 of Fig. 1 and looking in the direction of the arrow shown in Fig. 1. This view mainly illustrates one of a plurality of type head actuating mechanisms all of which are identical except in the shape of the key levers. This view shows a type head at impression point, the type head having three printing characters spaced apart one above another and the intermediate character being at the impression point. The view also indicates parts of the paper carriage shifting mechanism whereby the carriage is raised or lowered to bring the impression point of the platen in line with any one of the printing characters on the type head.

Fig. 3 is a view mainly showing a type head actuating mechanism with the type head in its most forward position away from the platen. The view also illustrates means for partially supporting the weight of the paper carriage, and is partially dotted in plan, in section at line 2—2 of Fig. 1.

Fig. 4 is a top plan view of a lengthwise (enlarged) adjustable, forked, supporting bracket with one of which each type head actuating mechanism is provided.

Fig. 5 is a side elevation of the bracket shown in Fig. 4.

Fig. 6 is an elevational view showing the rear end of the bracket shown in Figs. 4 and 5 in connection with the under end of a cam slotted toggle lever carried by it.

Fig. 7 is a top plan view, and

Fig. 8 a side elevational view of said cam slotted toggle lever which forms a member of the type head actuating mechanism.

Fig. 9 is a top plan view, and

Fig. 10 a side elevational view of a toggle member which connects a type head with a cam slotted toggle lever such as shown in Figs. 7 and 8.

Fig. 11 is a side elevation, and

Fig. 12 an end elevation of a bow shaped lever forming a member of a type head actuating mechanism.

5 Fig. 13 is a top edge view of a type head, and

Figs. 14 and 15 are respectively side and characterized elevations of the type head.

Fig. 16 is a top plan view of a flat, smooth 10 sheet metal, main frame forming blank. Fig. 17 is an end elevation of the sheet metal main frame formed from the blank shown in Fig. 16.

In that form of the invention now set 15 forth, (Figs. 16 and 17) the main frame or base of the machine is made from a stamped and bent sheet metal blank having a rectangular smooth horizontal top 1 which forms a level table on which the under edges 20 of the type heads are slidably supported.

The rectangular top 1 is provided with a lengthwise transversely extending arced slot 2, the concave side of which is rearwards. Members of a type head actuating mechanisms work through this slot.

The flat blank is bent along the dotted lines α to form the horizontal dependent end walls 3 of the base and also to form a rear dependent vertically slotted guide web 4 and 30 a front dependent vertically slotted guide web 5. The guide slots in each web are indicated by 6. The end forming portions 3 of the flat blank extend rearwardly beyond the rear edge of the web 4, and each 35 end portion 3 is formed with a recess 7.

Adjacent each junction of the dotted lines α inwardly of a corner portion of the rectangular portion 1, a corner of each web 4 and 5 is cut out at α' as required by the 40 punch and die. Dotted lines α^2 indicate lines for bending the flat blank to form inwardly projecting marginal portions 8 of the base. Each outward corner of the web 4 and of the web 5 is formed with a projecting lug 9, each having a pin hole 10 which 45 when the blank is bent into the base forming shape shown in Fig. 25 registers with a pin hole 11 in an end portion 3, whereby the dependent ends 3 and the dependent webs 50 4 and 5 of the blank when bent into base forming shape shown may be pinned or anchored together to keep the dependent members in fixed relation one to another. Of course, such anchorages of the dependent 55 members of the base may be otherwise effected than by the construction stated.

Referring to this sheet metal blank in its base forming shape, the upper end of each rear upstanding margin 8 is perforated at 60 12 for connection with the rear of a transverse rearwardly extending impression resisting and paper carriage guide bar described below. Each end 3 is perforated at 13 for 65 reception of a rear pivot of a swingable rocker arm carrying a cam roll of a paper

carriage shift mechanism. Similarly, the ends 3 are opposingly perforated at 14 for reception of a transverse cam carrying rocker shaft forming a part of the carriage shift mechanism. The under margin of the rear 70 guide web 4 is provided with a row of holes 15 each opposite the under end of a guide slot 6 and spaced apart by an imperforate marginal portion 16 of the web 4. The holes 15 severally receive the rear end of a coiled 75 spring forming part of the type head actuating mechanism, and the imperforate margin 16 closes the under ends of the guide slots 6 and the dependent guide web 4 is

bent downwardly and forwardly as indicated in Fig. 16. The ends 3 are opposingly formed with an anchorage hole 17 for the ends of a straight transverse rod on which the rear ends of the type head actuating levers are hooked. The rear ends 3 are also 80 formed with opposed bearing holes 18 for a straight transverse wiper cam carrying stationary pivot shaft, the wiper cams severally support the type head key actuating levers between the ends of the levers. So 85 also the ends 3 are opposingly formed with holes 19 for supporting the ends of a transverse rocker shaft that forms a member of the carriage shift mechanism. One of the ends 3 is formed near its rear upper corner 90 with a hole 20 for supporting a member of the carriage shift mechanism. The flat table-like top 1 of the base is formed with holes 21 in arced relation one to another adjacent the front edge of the arced opening 100 2 for support of vertical spacing means which support a transverse arced bar at the front of the machine and forwardly of the opening for carrying a series of brackets 105 each forming a part of a type head actuating mechanism. Rearwardly of the opening 2, the top 1 is formed with openings 21^a for reception of vertical spacing means which carry an upper demountable transversely extending arced type head cover plate. The rearward corner projections of the flat 110 blank are formed with right angular recesses, one wall 22 of which forms a horizontal bearing for an end of the impression blow resisting and carriage guide bar, and the rear upstanding edge 23 of which forms a rear abutment or bearing for an end of such bar.

Referring to Fig. 2, upright vertical spaces 24 are severally located at each hole 21 of the base, and a screw 24^a passes upwardly through a hole 21 and through the bore of a spacer into a transverse, arced, horizontal bracket supporting bar 25 at the front side of the machine, the rear concave edge of this bar being approximately coincident with the rear edge of the arced opening 2 through the base top 1. The front edge of the bracket supporting bar 25 is provided with a series of threaded openings, 130

each for a bracket adjusting screw 26, the head of which projects above the upper surface of the bar.

The type heads are reciprocated in radial paths to the impression point, and the type head actuating mechanisms are, except for the transverse shape of their key levers, identical one with another in construction and mode of operation.

- 10 Each type head actuating mechanism comprises a bracket 27 (Figs. 4, 5 and 6) having a dependent arm 28 and a rearward lug 29. Its forward under corner is provided with a shoulder 30 for engagement with the head 15 of the adjusting screw 26. Its forward upper portion is provided with an elongated slot 31 and its rear end lug 29 is forked to form a forked space 32 from top to bottom of the rear end of the lug 29, which 20 over-hangs the opening 2 through the base top. Each bracket 27 is held to the bar 25 by a clamp screw 27^a through the elongated slot 31. By loosening the screw 27^a and adjusting the adjusting screw 26, the bracket 25 27 may be endwise adjusted for adjustment of a type head in operative connection with the bracket. By a transverse pivot pin 33 the forward transversely perforated lug 34 of a front cam toggle lever 35 is pivoted in 30 the forked space 32 of the bracket, the fork arms of which over-lap the lug 34 and keep it from lateral vibration during its movements. This toggle member 35 has, opposite the lug 34, a projecting horn 36 at the base 35 of which is a pivot hole 36^a for reception of a transverse pivot pin 34^a. This toggle member 35 has a lengthwise curved cam slot 37. In the assemblage, the pivot pin 34^a pivotally connects the front end of a rear 40 toggle member 38 in the form of a link having front fork arms 39 and rearward fork arms 40, each of which has near its rear end a hook 41, one hook being laterally opposed to the other and the hooks being open on 45 the upper side of this toggle member or link 38. The fork arms 39 receive between them the body of the front cam toggle member 35 rearwardly of the pivot pin 34^a, the horn 36 being slidable between the fork arms 39 50 whereby at this point of the mechanism lateral vibration adjacent the pivot pin 34^a of the two toggle members, one in relation to the other, is overcome. The rearward fork arms 40 of the rear toggle member 38 55 receive the type head carrier; the type head itself being indicated by 42 and being shown with three printing characters spaced apart vertically one above the other. The carrier itself is indicated by 43, and is a short rectangular plate, the weight of which is reduced by an opening α in its body. This plate is thin, and has an upper and also a lower forwardly extending arm 44, the arms being made as short as feasible and vertically connected by an integral, upright mem-

ber 45. Midway between the upper and under edges of the members 44 the carrier is provided with a transverse pin 46 which projects on each side of the carrier. The fork arms 40 of the rearward toggle member 70 38 receive the type head carrier 43, the hooks 41 of the toggle member receiving the ends of the pin 46. Which is closely adjacent the printing characters on the rear vertical edge 75 of the type head. By spanning or embracing in sliding connection the sides of the type head carrier 43 the fork arms 40 of the rear toggle member 38 at all times prevent lateral wobbling or vibration of the type head which, in operation, is reciprocated 80 back and forth on the smooth surface of the base top 1, towards, and from the platen P. The upper edges of the members 44 of all the type heads are covered by and are in sliding contact with the under surface of 85 a transverse arced type head cover plate 48, the ends of which are held to the base top 1 by screws 49 through upright spacers 50 resting on the base top 1, this cover plate being mounted rearwardly of the opening 90 2 in the base top. The screws 49, or other fasteners, are anchored in the base top and the plate 48 is readily detachable. The under edges of the hooks 41 are curved at 95 41^a and in the working assemblage bear 100 upon the ends of a transverse pin 47 through and projecting from each side of the type head carrier below the pin 46. This construction permits the type heads and carriers to be quickly disconnected with the 105 toggle members 38 on removal of the cover plate 48, and by this means permits the machine to be provided with a series of type heads of any desired style of printing character in a given language, and also permits 110 type heads carrying the printing characters of one language to be readily substituted for type heads carrying the printing characters of another language, whereby the machine becomes adapted for use in writing in various languages and styles for various commercial and other purposes. The fork arm construction referred to, by keeping the parts from lateral wobbling, maintains the 115 type heads and carriers in upright position, and makes it unnecessary to form the flat smooth horizontal base top 1 on its upper surface with radial guide grooves, and to form the under surface of the cover plate 48 with corresponding guide grooves for the 120 type head carriers, and this obviates a considerable item of expense heretofore attending production of toggle link actuated type heads and involved in the milling of upper and under, either or both, radial guide 125 grooves for guiding the reciprocating type heads to the impression point. The forward cam toggle member 35 is vibrated for reciprocating the type head to and from the impression point by means of a suitable lever, 130

link and impression key construction in which, as now shown, a bow shaped lever 51 has its forward and under end provided with a pivot pin hole for reception of a pivot pin 52, by which the lever is pivotally connected to the under end of the dependent arm 28 of bracket 27. The bow shaped lever 51 is made up of two side plates, which at one end embrace the under end of the arm 28, and are thereby spaced apart and also held together in sliding relation to the sides of the dependent arm 28 by the pivot pin 52, the other end of the two plates which constitute the bow 51 being spaced apart by a cam roll 53 and held together by a cam roll pivot pin 54. The cam roll 53 works in the cam slot 37 of the front toggle member and the side plates of the bow shaped lever embrace the rearward walls of the forward cam lever and thereby assist in keeping the toggle members and the type head carrier from the lateral wobbling or vibration above referred to. The sides of the dependent arm 28 are spaced apart by a spacer 51^a which is riveted in place at 28^a.

To the bow shaped lever, between its ends, there is pivoted at 55 the upper end of a dependent link 56, the under end of which is pivoted at 57 to an impression key lever 58. The bow shaped lever 51 and its link work through the opening 2 in the base plate top and the impression key lever 58 is located below the top of the base. The impression key lever 58 is formed, at its rear end, with a dependent integral lug 59 and is also formed, at its upper rear corner with a re-entrant recess 60 in its upper edge which permits the impression key lever and all of them to be hooked upwardly against the transverse impression key lever pivot rod 61, which extends straight across the machine and has its ends anchored in the holes 17 of the base ends 3. The impression key lever 58 has, near its front end, an integral dependent projection 62, its front end being upturned and provided with a button head 63. The downward projections 59 and 62 of the impression key lever, which is made of thin sheet metal, are located in and in all positions work between and in sliding contact with the edge walls of the slots 6 respectively in the rear dependent web 4 and in the front dependent web 5 of the sheet metal base. Thus the impression key lever is, at its rear end and adjacent its front end, kept from lateral movement during operation; and it is particularly in this connection that the integral formation of the guide slot members 4 and 5 of the sheet metal frame becomes of considerable working importance, because if these front and rear slotted guides were made in pieces separate from the frame and thereto connected by screws, or other fasteners, they would be apt to work loose to some extent during the opera-

tion of the machine, and involve adjustment from time to time in order to keep all the above described members of the series of type head actuating mechanisms from such lateral wobbling or movement as would tend to throw the type off their feet at the impression point. But, obviously the desirable rigidity of the slotted guide members 4 and 5 of the frame might be effected by welding or brazing them as separate pieces to the frame in order to give them the desired and proper rigidity. Each impression key lever 58 rests, in the present construction in bearing contact, on a rockable, ovalish shaped wiper cam 64, the under end portion of which is pivoted on a transverse straight stationary shaft 64^a, the ends of which are fixed in the holes 18 of the base ends 3. The forward camming surface 65 of the upwardly extending wiper cam 64 contacts with the under edge of the impression key lever 58; and the rear cam edge 66 of the wiper cam co-operates with an impression key lever return spring, the under edge of the wiper cam below the pivot shaft 64^a being provided with a lug 67 in which the forward end of a forwardly straight portion 68 of a coiled spring 69 is connected. The rear end of the return spring 69 is anchored in the hole 15 in the marginal portion 16 of the rear dependent base web 4. Whenever an impression key lever is depressed against the wiper cam, with which its under edge is in constant contact by reason of the tension of the coiled spring 69, the wiper cam is correspondingly depressed to rock the cam surface 66 gently and progressively upon the straight portion 68 of the spring to increase the tension thereof. Hence, the operation of the machine in this respect is at all times silent. It will be observed that because of the short length of the type head carrier the type head actuating mechanism may be made exceedingly short, whereby a very compact or narrow machine from front to rear is obtainable, with a decrease in its weight, compared to prior art machines having toggle length impression key actuating mechanisms.

As already indicated, the effectiveness of the present machine for use in manifolding is greatly enhanced by connecting the type heads closely adjacent the printing characters to the toggle link members, the effective impression behavior of which is also enhanced by the relatively short length construction of the several identical type head actuating units or mechanisms assembled in the complete machines, and which are provided with a standard key-board having three parallel rows of impression keys at the front of the machine and in rear of the usual spacer bar S indicated in Fig. 1. For silencing the forward movement of the type head actuating mechanism I mount an

arcuate thin sheet metal pad carrier 70 which is L shaped in cross-section on and over the upper edges of the bracket 27, clamping the under horizontal web of the carrier 70 to the brackets by the screws 27^a, and providing the pad carrier with an arced shape upstanding pad 71 of soft material, the rearward face of which forms an abutment for the front edges of the forward toggle link or member 35, and the co-operating forward end portion 39 of the rearward toggle link or member 38, so that when the coiled spring 69, which is put under tension by a depression of the key lever, causes the wiper cam to move upwardly and thereby rock the therewith connected link 56, bow lever 51, cam toggle member 35 and rear toggle member 38 forwardly, the shock attending such movement is absorbed by the pad 71 with its wall opposed to all the impression key actuating mechanisms.

It is desirable to provide the base top 1, about midway between its ends, with a brace provided with bearings for transverse rocker and stationary shafts comprised in the machine, and this brace is indicated by 72. It has horizontal end flanges which are fixed rearwardly at 73 to the under surface of the base top, and forwardly at 74 to the under surface of the base top by one of the screws 24^a. It is shown recessed on its upper edge, and provided with a rearward extension, having a flange 72^a abutted against the margin 16 of the rear dependent guide web 4. Its under edge is provided with a hole through which the pivot shaft 64^a passes in fixed contact, and forwardly thereof with another hole forming a bearing for a rocker shaft to be described. This brace adds to the rigidity of the frame and of the rear vertical slotted guide web 4 of the base.

The platen P is, as usual, carried by an endwise movable paper carriage having vertical end plates 75, a transverse back member 76, and on its rear side a straight bearing web 77 in sliding contact with the forward wall of a straight transverse impression blow resisting and carriage guide bar 78, which in the present construction is anchored on the horizontal walls 22 of the base ends 3, and supported at each end by such walls and rearwardly by the vertical walls 23 of the base ends, secured by rivets in holes 12.

I do not herein show, either in connection with the spacer bar S or otherwise, any escapement mechanism for moving the paper carriage endwise. Such escapement mechanism does not form a feature of my present invention. I do, however, indicate in the drawings an escapement rack bar R of usual construction in its proper location.

For shifting the paper carriage and platen vertically to bring the impression point into opposition to any one of the three printing

characters on the vertical face of the type head, the vertical end plates 75 of the paper carriage are transversely rigidly connected by a tube 79, the under wall of which is lengthwise slotted at 80. The slotted tube 79 is mounted slidably on a transverse rod 81, end portions of which are each fixed to the upturned end 82 of a rocker arm 83, the two rocker arms 83 being each pivoted at their rear ends on studs 84 fixed in holes 13 of a base end 3. Thus the paper carriage is endwise movable on the transverse oscillatable supporting rod 81, carried by the forward ends of the rocker arms that project from the rear side of the machine into the transversely extending paper carriage path, the paper carriage having its ends projectable beyond the base ends by reason of the base end depressions at 7.

Between its ends each rocker arm 83 carries a laterally projecting cam roll 85; one of the cam rolls at the right hand end of the machine working in a cam path 86 of a rocking cam 87 which, in Fig. 1, is located at the under end of the drawings, which is the right hand end of the machine as one faces the key-board. This cam 87 is fixed on one end of a straight transverse rocker shaft 88, the ends of which are journaled in the opposed bearing holes 14 of the base frame 95 near the rear under corners thereof.

A corresponding cam 87^a for the carriage shift mechanism is mounted on the normally left hand end of the rocker shaft 88, as indicated in Fig. 1.

Returning to the cam 87, it has pivoted to it at 89 above the rock shaft 88, the rear end of a forwardly extending link 90, the forward end of which is pivoted at 91 to the under end of a rocker arm 92 of the rocker shaft 93 which is journaled in the holes 19 of the base ends 3. The carriage shift mechanism described below comprises a shift key lever, depression of which rocks the shaft 93 and consequently rocks the cams 110 87 and 87^a.

Outwardly of the right hand cam 87, the rocker shaft 93 has fixed to it a cross-bar 93^a each end of which is provided with a buffer roll 94 which is positioned to come 115 into silent contact with a buffer pad 95, located forwardly of the buffer rolls.

The impression key levers are variously bent between their ends as at y (Fig. 1) in order that the rear end portions thereof may be straight and parallel one to another, for some distance forwardly of the transverse pivot rod 61 on which they are hooked, and at the same time be operative to effect the radial travel of the type heads to the impression point; and also have their free ends provided with the impression key tops K² arranged in rows as in a standard key-board, and as illustrated in Fig. 1; and an important reason for having the rear end 13v

6 portions y' of the impression key levers straight and parallel is that they may therefore be in a position for properly contacting with the front edges 65 of the wiper cams 64, 5 which are laterally parallel one with another and project at right angles to the axis of the stationary transverse pivot shaft 64^a on which they are loosely mounted. These wiper cams are in lateral sliding contact one with another, and at the opposite ends of the series of wiper cams, they are held in place by collars 128, as indicated in Fig. 1, on the front shaft 61^a.

10 While the paper carriage member 77 is always in sliding contact with the transverse bar 78, the slight arc of movement given to the axis of the carriage supporting rod 81 does not, in practice, cause the member 77 to bind against the bar 78, and it is to be noted that the rack bar R is fixed to the 15 slit tube 79 and forms a fixed member of the paper carriage.

15 The rear vertical portion of the carrier 43 has a forward enlargement 43^a whereby 20 the rear or printing character carrying end of the short type head is stiffened sufficiently to form a pivot pin bearing so that the pivot pin 46 is easily made stiff and rigid enough for efficient working relations 25 between its ends and the walls of the hook recess 41. By the fork arm construction and lateral bearing surface arrangement, already described, of the toggle links comprised in the type head actuating mechanism 30 as well as of the type head with one of the toggle links and also of the bow shaped toggle link actuating lever 51 and the similar arrangement of the forward toggle link member 35 with the bracket 27, 35 these members of the type head actuating mechanism are laterally self-resistant to those lateral vibrations which would impair 40 impression if they existed; and while toggle link members are old in a silently operating typewriter for moving a type head radially 45 to an impression point when its key lever is depressed, yet, in the present construction, so far as I am advised, what I have referred 50 to as a construction that is laterally self-resistant against the undesirable lateral wobbling of these members is new in the 55 present construction. It is also important because it enables these members to be automatically sustained in proper working relation 60 one to another and to the impression point without going to the expense of milling guide grooves for the type heads in the under and end type head supporting plates; and with a type head of the short length 65 now proposed, to wit; of about 1" in actual practice, it would be impossible to provide the table top 1 and the cover plate 46 with vertically opposed radial guide grooves that 70 would not necessarily run one into the other

as they approached convergingly near to 65 the printing point.

70 Where, as in the prior art comparable construction, the type heads have been of an actual working length of 2½", it has been mechanically possible, as is well known, to 75 form independent guide grooves such as alluded to, without the guiding grooves running one into another adjacent the printing point at which the guide grooves are convergent. Therefore, by shortening the type 80 heads as already indicated, I produce a more compact machine, reduce its weight and obviate the expense of milling the type head supporting plates in order to produce guide 85 grooves, and by making the principal moving members of each type head actuating member or unit laterally self-sustaining I obtain that full lateral control for prevention of lateral wobbling which is so essential. 90

95 The rear edge of the smooth surface table top is provided midway between its ends and closely adjacent the printing point on the platen with upstanding type head side guides 1^a of known form but forwardly of 90 these upstanding guides which are useful merely closely adjacent to and at the moment of impression, the table top is plain surfaced. The type-head side guides 1^a are impression point guides for the type-heads, 95 but between these guides and the slot 2 the table top 1, or type-head under supporting plate, and the cover plate 48, are smooth surfaced, and the under and upper edges of each type-head are laterally unguided by 100 guide-way forming members during their reciprocation from their most forward positions to the impression guides 1^a. Due to the anti-wobbling guidance of the toggle link members, each type-head may be reciprocated properly to the printing point, yet each of the so actuated type-heads has such a capacity of lateral movement that if a plurality of them are accidentally driven simultaneously to the impression point, they 105 will be severally drawn back by their return springs. This capacity of what may be called automatic release and return from lateral contact of two or more type-heads 110 at the impression point, is of demonstrated practical importance for high speed work on machines embodying this invention. 115

What I claim is:

120 1. In a typewriting machine, the combination of a pivoted impression key-lever; a pivoted wiper-cam provided with opposed and upper and under cam surfaces and located with the upper cam surface in the path of the impression key-lever and with the under cam surface opposed to a straight 125 portion of a coiled return spring, the key lever bearing continuously on the upper cam surface; and said coiled return spring.

mounted with its straight portion in the path of the under cam surface and having one end anchored to the machine frame and the end of its straight portion connected to the wiper cam.

2. In a typewriting machine, the combination of a platen; a series of pairs of inter-bearing toggle links resistant at their connections to lateral movement, each pair of toggle links being operatively connected with a toggle link actuating lever operatively connected with an impression key lever; such toggle link actuating lever and such impression key lever; a substantially short length type-head operatively connected with one of each toggle links closely adjacent a printing character of a type-head and forwardly of such printing character, the type-head having a forwardly projecting portion embraced between a forked rear end portion of the toggle link connected to the type-head; a flat surfaced under support for all the type-heads, the type-heads being laterally unguided in their reciprocation to and from the impression point except by interbearing relations each to the toggle link with which it is connected; whereby a plurality of type-heads if forced simultaneously to the impression point into contact one with another, will be then movable sidewise for several automatic return under the influence each of a return spring; and for each type-head actuating mechanism a return spring.

3. In a typewriting machine the combination of a sheet metal main frame having integral dependent end supports and integral dependent vertically slotted side webs and integral laterally opposed rearwardly extending members oppositely recessed on their upper edges to permit an endwise movable paper carriage to be projected endwise beyond either end of the frame; an endwise movable, vertically adjustable paper carriage; a paper carriage shifting mechanism; a type-head provided with a plurality of printing characters spaced apart one from another and reciprocatable from and towards the printing point in a path radial to the printing path; a type head actuating mechanism comprising a key lever pivotally mounted under the main frame, the latter having an opening for upward extension of and to permit the working through said slot of a member of the type-head actuating mechanism; and the impression key lever being mounted for lateral restraint in the vertical slots of the dependent slotted webs of the frame.

4. In a typewriting machine the combination of a sheet metal main frame having integral dependent end supports and integral dependent vertically slotted webs and integral laterally opposed rearwardly extending members oppositely recessed on their

upper edges to permit an endwise movable paper carriage to be projected endwise beyond either end of the frame; an endwise movable, vertically adjustable paper carriage; a paper carriage shifting mechanism; 70 a type head provided with a plurality of printing characters spaced apart one from another and reciprocatable from and towards the printing point in a path radial to the printing path; a type head actuating mechanism comprising a key lever pivotally mounted under the main frame, the latter having an opening for upward extension of and to permit the working through said slot of a member of the type head actuating mechanism, such mechanism comprising toggle link members; and the impression key lever being mounted for lateral restraint in the vertical slots of the dependent slotted webs of the frame. 80

5. In a typewriting machine the combination of a sheet metal main frame having a smooth surfaced horizontal top, integral dependent supporting members and integral dependent webs vertically slotted; a vertically shiftable paper carriage; a paper carriage shifting mechanism; a type head reciprocatable over said smooth surfaced horizontal top, and provided with a plurality of printing characters spaced apart one above another; and a type head actuating mechanism comprising toggle links and an impression key lever pivotally mounted below said top and having lateral surfaces working in said vertical slots. 90

6. In the combination stated in claim 5, the type head actuating mechanism members being constructed, mounted and operable with laterally opposed contact bearing surfaces operable to make the members laterally self-sustaining without contact of lateral margins of the type head with guiding means forwardly of type head guides closely adjacent the printing point; and type head guides for the type head and fixed to 105 said top closely adjacent the printing point.

7. As a new article of manufacture, a sheet metal main frame for a typewriting machine comprising a horizontal table top formed with an arced opening, the concave 115 edge of which is rearwards and which has other edges radial to the center of the circle from which the arc is struck, and having integral, dependent end supports and an integral, dependent, vertically slotted guide 120 web.

8. As a new article of manufacture, a sheet metal main frame for a typewriting machine comprising a horizontal table top; integral, dependent end supports; integral, 125 dependent front and rear vertically slotted guide webs spaced apart one from another; and an integral rearward edgewise upstanding extension of each dependent end support, such extensions being laterally opposed 130

one to the other and each having an upper edge portion at a level lower than the table top.

9. As a new article of manufacture, a sheet metal main frame for a typewriting machine comprising a horizontal table top; integral, dependent end supports; integral, dependent front and rear vertically slotted guide webs spaced apart one from another; 10 and an integral rearward edgewise upstanding extension of each dependent end support, such extensions being laterally opposed one to the other and each having an upper edge portion at a level lower than the table top; 15 and rearward thereof an upstanding back corner portion, the top of which is higher than the table top.

10. In a typewriting machine, the combination of an impression key lever; a return

spring; a toggle link type-head actuating mechanism comprising a type-head, such mechanism being operatively connected with the impression key lever; a smooth-surfaced support for the type-head and a platen; closely adjacent the impression point of the platen, type-head guides for controlling the type-head at the time of impression when the toggle links are aligned, said guides being spaced apart from the retracted position of the type-head and the type-head being laterally unguided between its forward retracted position and its position under control of said guides at the time of impression. 20 25 30

Signed at New York city, in the county of New York and State of New York, this 35 14th day of June, A. D. 1921.

WELLINGTON PARKER KIDDER.
